UNITED STATES PATENT OFFICE.

JOHN C. BEACH, OF SAN FRANCISCO, CALIFORNIA, ASSIGNOR TO LACHMAN WALL BED COMPANY, OF SAN FRANCISCO, CALIFORNIA, A CORPORATION OF CALIFORNIA.

FOLDING BED.

1,267,045.

Specification of Letters Patent. Patented May 21, 1918.

Application filed January 26, 1916. Serial No. 74,357.

To all whom it may concern:

Be it known that I, JOHN C. BEACH, a citizen of the United States, residing at the city and county of San Francisco and State 5 of California, have invented new and useful Improvements in Folding Beds, of which the following is a specification.

This invention relates to folding beds; and has for its object to improve and simplify 10 the construction and operation thereof.

In carrying out this object, I employ a base-plate fitted with a head piece rigidly connected thereto, a frame carried intermediate its length by pivoted suspension links 15 depending from the corner posts of the head-frame, vertical track members on the corner posts, upon which rollers, carried by a front end-piece on the main frame, operate, counterbalancing springs between the 20 main frame and the base-plate, and double acting springs between the corner posts and main frame, the latter operable at either extremity of movement of the main frame to cushion the same, and a frame carried 25 upon supports extending vertically from the head frame for suspending a curtain to conceal the folded bed.

One form which my invention may assume is exemplified in the following description and illustrated in the accompanying drawings, in which—

Figure 1 shows a rear elevation of a device embodying my invention.

Fig. 2 shows a detail perspective of a portion 35 of the curtain-carrying frame.

Fig. 3 shows a side elevation of the front portion of the bed shown in Fig. 1.

Fig. 4 shows a similar view, with the parts in folded position.

Fig. 5 shows a detail perspective of the 40 swinging connecting link for one of the counterbalancing springs.

Fig. 6 shows a sectional view, taken on the line 6—6 of Fig. 4.

Referring now in detail to the device illustrated herewith, I have shown base-plates 10 suitably secured to the floor and carrying upright posts 11 rigidly supported by adjustable brace-bars 12, said posts forming, 45 in connection with a cross member 13, the head-frame of the bed. A main frame 14 is pivoted at 15 to suspension links 16, the latter being pivoted at 17 to the upright posts 11. The pivot 15 forms a floating

pivot on which the main frame turns. The 55 usual folding foot-piece and supporting legs for the opposite end of the main frame are employed, although not shown in the drawings.

The front end of the main frame has 60 upwardly projecting bracket members 18 at its sides carrying between them a front end-piece 19. Journaled upon the upper corners of the brackets 18 are rollers 20 working against vertical tracks or rails 21 fitted to 65 the inside of each post 11 and serving to guide the main frame in its pivotal movement.

Double acting contractile coil springs 22 are provided for the purpose of counter- 70 balancing the bed-frame in extended position and also cushioning it in its folded position. These are arranged, one at each side of the frame between the front end-piece 19 and the adjacent corner post 11, 75 being connected to lugs 23 fixed upon the former at the top thereof and spaced inwardly from the end and to the latter by screw eyes 24 fixed to the post midway between the extremities of movement of the 80 lugs 23. By having the springs 22 occupy an oblique position at either side of the center of movement of the front end-piece they will be under tension during a longer period at or near the extremities of move- 85 ment.

A set of auxiliary counterbalancing springs 25, preferably two in each set, is arranged between the main frame and base-plate at each side, being connected to the 90 former by swinging lugs 26 pivoted to yokes 27 carried on the lower front end of the main frame, as shown in detail in Fig. 5, and to the latter by perforated plates 28 located on the rear side of the base-plates. 95 In the extended position of the main frame the springs 25 are under tension, as shown in Fig. 3, and in folded position they are retracted to lie flatly upon the floor as shown in Fig. 4, on account of the swinging movement of the lugs 26. Thus the said springs 25 aid the springs 22 in the lifting movement of the main frame when the latter is in extended position.

In the operation of the device so far described, it will be seen that the main frame, when in folded position, will rest upon the base-plates 10 at its front end, at which

time the springs 25 will be retracted and lie between the said end-piece and base plates, while the springs 22 will be under tension, as shown in Fig. 4. To extend the main frame for use, the operator moves the said frame outwardly from the head-frame, at which time the rollers 20 will ride upon the tracks 21, causing the main frame to be thrust bodily outward in its pivotal movement. The initial movement of the bed-frame from folded position will be assisted by the springs 22 and the said springs, at their ends where they connect to the vertically movable portion of the main frame, will be carried past their fixed connections with the corner posts and again be placed under tension near the extremity of movement of the main frame in extended position.

When extended the main frame is supported at its forward end by the suspension links 16 and held in proper spaced relation with the head-frame by reason of the rollers 20 engaging the guide rails 21 and the springs 25, as well as the springs 22, will be under tension at this time so that the weight of the main frame is nearly balanced.

Removably carried in sockets 29, fitted upon the head-frame, are vertical supporting rods 30 provided at their upper ends with a rodded frame 31, the latter approximately U-shaped in outline, from which is suspended, by means of rings 32, a curtain or other device 33 for concealing the bed when the latter is in folded position. Thus the article is complete in itself, furnishing its own supporting base and closure and for this reason may be positioned any place in a room without special provision being made for its reception.

While I have shown and described but one form herein, it will be understood that the device is capable of modification and, therefore, many changes in the construction and arrangement of the several parts may be employed without departing from the spirit of my invention as disclosed in the appended claims.

Having thus described my invention, what I claim and desire to secure by Letters Patent is:—

1. In a folding-bed, the combination of a stationary head-frame, a movable main frame, suspension links pivotally connected between said frames for supporting the front end of the main frame in extended position, guide members between the frames for maintaining the main frame in proper spaced relation with the head-frame, and counterbalancing springs connected between the main frame and the head-frame adapted to be placed under substantially the same tension at each extremity of movement of the main frame.

2. In a folding-bed, the combination of a

stationary head-frame, a movable main frame, suspension links pivotally connected between said frames for supporting the front end of the main frame in extended position, guide members between the frames for maintaining the main frame in proper spaced relation with the head-frame, counterbalancing springs connected between the main frame and the head-frame adapted to be placed under substantially equal tension at each extremity of movement of the main frame, and auxiliary springs between said frames for aiding the first-mentioned springs at the beginning of the folding movement of the main frame.

3. In a folding-bed, the combination of a stationary head-frame and a movable main frame, pivotal connections between said frames to permit folding movement, and diagonally extending contractile coil springs connecting the ends of the head-frame with the intermediate portions of the front end of the main frame and movable with the latter to substantially equal distances at opposite sides of their fixed connection for cushioning the movements of the main frame at either extremity of its position.

4. In a folding-bed, the combination of a stationary head-frame, a main frame pivotally connected thereto, vertically slidable connections between the front end of the main frame and the head-frame, counterbalancing springs connected to the head-frame and to the vertically movable portion of the main frame, whereby one end of each spring is carried with the main frame to substantially equal distances at opposite sides of the fixed connection with the head-frame to cushion the movements of the main frame at the extremity of either position of movement.

5. In a folding-bed, the combination of a stationary head-frame, a main frame pivotally and foldably connected therewith, contractile coil springs connecting the said frames and movable with the main frame to substantially equal distances at opposite sides of their fixed connections for cushioning the movements of the same at either extremity, and auxiliary springs connected between the said frames for counterbalancing the main frame in extended position.

6. In a folding-bed, the combination of a base-plate, a head frame rigid therewith, a movable main frame, rollers on opposite sides of the front end of said main frame, vertical guide rails on opposite sides of the bed-frame against which said rollers operate, a floating pivot on which the main frame is adapted to turn so that the frame may be moved to folded position on the head frame with its front end resting upon the bed-plate and to extended position with its front end supported upon said floating pivot, a coil spring connecting the head- 130

frame and main frame for cushioning the movements of the main frame at either extremity of its position.

7. In a folding-bed, the combination of a base-plate, a head frame rigid therewith, a movable main frame, rollers on opposite sides of the front end of said main frame, vertical guide rails on opposite sides of the bed-frame against which said rollers operate, a floating pivot on which the main frame is adapted to turn so that the frame may be moved to folded position on the head frame with its front end resting upon the bed-plate and to extended position with its front end supported upon said floating pivot, a coil spring connecting the head-frame and main frame, and movable with the latter to substantially equal distances at opposite sides of its fixed connection for cushioning the movement of the main frame at either extremity of its position.

8. In a folding-bed, the combination of a base-plate, a head frame rigid therewith, a movable main frame, rollers on opposite sides of the front end of said main frame, vertical guide rails on opposite sides of the bed-frame against which said rollers operate, a floating pivot on which the main frame is adapted to turn so that the frame may be moved to folded position on the head frame with its front end resting upon the bed-plate and to extended position with its front end supported upon said floating pivot, a coil spring connecting the head-frame and main frame for cushioning the movements of the main frame at either extremity of its position, and an auxiliary spring connected to said frames for assisting said other spring in counter-balancing the main frame in extended position.

9. In a folding-bed, the combination of a base-plate, a head frame rigid therewith, a movable main frame, rollers on opposite sides of the front end of said main frame, vertical guide rails on opposite sides of the bed-frame against which said rollers operate, a floating pivot on which the main frame is adapted to turn so that the frame may be moved to folded position on the head frame with its front end resting upon the bed-plate and to extended position with its front end supported upon said floating pivot, a coil spring connecting the head frame and main frame and movable with the latter to substantially equal distances at opposite sides of its fixed connection for cushioning the movement of the main frame at either extremity of its position, and an auxiliary spring connected to said frames for assisting said other spring in counter-balancing the main frame in extended position.

10. In a folding bed, the combination of

a stationary head-frame, a movable main frame, vertical tracks on the head-frame, 65 rollers carried by the main frame and operating against said tracks, swinging suspension links pivotally connected between the head-frame and the front end of the main frame, whereby to provide fulcrum 70 supports for the latter movable downwardly when the bed is folded and upwardly when the bed is unfolded, and counterbalancing springs operable to appreciably assist both the folding and unfolding movements of the 75 main frame.

11. In a folding bed, the combination of a stationary head frame, a movable main frame, vertical tracks on the head frame, rigid suspension links pivoted at one end 80 to the front end of the main frame and at the opposite end to the head frame above and in alignment with the tracks, counter-balancing springs operable to assist to an appreciable degree both the folding and unfolding movements of the main frame, and rollers operable on the vertical tracks and journaled on the front end of the main frame in advance of the pivotal connection between the suspension links and the head 90 frame.

12. In a folding bed, the combination of a stationary head frame, a movable main frame, vertical track and roller connections between said frames, swinging suspension 95 links between said frames upon which the main frame is supported and forming fulcrum supports therefor movable downwardly when the bed is folded and upwardly when the bed is unfolded, means 100 for counterbalancing the main frame in extended position, and means for assisting in the unfolding movement of the main frame.

13. In a folding bed, a head frame provided with a vertical track, a main frame, a 105 roller secured to the latter for operating on the track, suspension links pivotally connecting the main frame to the head frame, spring means connected at one end to the main frame adjacent the roller and at its 110 opposite end to the head frame intermediate the ends of the path of travel of the roller, and other spring means secured at one end to the main frame at a point, when the latter is horizontally disposed, below the point 115 of securement of the first spring means to the main frame and at its opposite end to the lower portion of head frame.

In testimony whereof I have hereunto set my hand in the presence of two subscribing 120 witnesses.
